UNITED STATES PATENT OFFICE

140,939

DESIGN FOR A BRACELET OR SIMILAR ARTICLE

William W. Hobé, New York, N. Y.

Application January 27, 1945, Serial No. 117,641

Term of patent 7 years

(Cl. D45—4)

To all whom it may concern:

Be it known that I, William W. Hobé, a citizen of the United States of America, residing in New York city, county of New York, and State of New York, have invented a new, original, and ornamental Design for a Bracelet or Similar Article, of which the following is a specification, reference being had to the accompanying drawing, forming part thereof, wherein,

I claim:

The ornamental design for a bracelet or similar article, substantially as shown.

WILLIAM W. HOBÉ.
